UNITED STATES PATENT OFFICE.

JOHN H. REEDY, OF HAMILTON, OHIO, ASSIGNOR TO THE CHAMPION COATED PAPER COMPANY, OF HAMILTON, OHIO, A CORPORATION OF OHIO.

JOURNAL BOX.

Application filed August 8, 1924. Serial No. 730,799.

My invention relates to an adjustable, watercooled journal bearing having bearing surfaces that are adjustable to accommodate shafts of varying dimensions and adjustable to compensate for wear of the shaft or of the bearing surfaces of the journal box. Furthermore, by means of the several adjustments possible in my invention the shaft may be kept in perfect alignment with other elements of the machine, to which it is applied and wear in them compensated for from time to time by re-adjustments in the journal box.

It is also my object to provide an adjustable means for locating the journal box in a desired place and especially where a sliding or shifting journal is required to permit close contact with the runways in which the journal operates.

My invention as shown in the drawings and described in the specifications is mainly intended for use in a web calender machine commonly used in paper mills for finishing and surfacing paper, but I do not wish this to be construed to limit my invention to this particular use, and desire the full benefit and protection under the laws of the United States, for its use in any other mechanism where such a journal may be desirable and practical.

In further and more detailed description of my invention and its use, permit me to explain that a web calender machine is a device for the purpose of finishing the surfaces of certain paper and providing it with a highly smooth and glossy surface suitable for certain classes of printing to be done thereon. This is accomplished by passing the paper between a series of rolls stacked one above the other and rotatably journaled in a framework.

These rolls are made of chilled cast iron and have highly polished surfaces and their journals are slidably located in runways in the framework of the machine so that the rolls rest one upon the other and upon the paper passing through between them thus, by their weight, providing the necessary pressure upon the paper to be finished.

It is to be understood that after a period of continuous service at the high speed which is necessary for the successful operation, the shaft ends and journal bearings will show considerable wear, and the resultant play in the journal will throw the

roll out of alignment. In calenders now in use these journal bearings are either permanently fixed in the journal and not capable of adjustment, in which case the entire journal box has to be removed in order to resurface these bearings, or where the bearings are adjustable, they are difficult of access and in either case require not only a great deal of labor and time for making these repairs, besides necessitating the shutting down of the calender during the time repairs of this kind are made. In view of the fact that the rolls run in contact and thus in opposite directions, the tendency is to wear one side of the journal more than the other and for alternate rolls to wear alternate sides of the journals, so that misalignment tendency is very strong in web calendering machines.

It is the purpose of my invention to permit adjustments of bearing surfaces of the journals to be made effectively and rapidly and if desired, while the machine is in operation.

The wear in the rolls themselves moreover, will at some time necessitate the refinishing of their surfaces and in this process it is obvious that the circumferential dimensions of the roll will be reduced, so that in order that the rolls may be allowed to bear one upon the other, the journal boxes must be compactly constructed, thus permitting them to be closely stacked in the framework. In my invention I have accomplished this desired degree of compactness thus assuring long use and repeated possibility of refinishing the rolls before replacement by new rolls becomes necessary.

As the above stated calenders of this type are necessarily run at high speed to accomplish the best results in the finished product and the matter of cooling and lubricating, the bearings under such conditions become a factor in the life of these bearings and in the economy of operation of the machine.

It is, therefore, the purpose of my invention to provide a water cooling system by means of which water is circulated under pressure through channels adjacent to the main-bearing surfaces. Furthermore, the construction of the housing of my journal box is designed to permit the shaft ends of the rolls to run in an oil bath, the oil being supplied by means of a pump to the uppermost journal and passed by gravity to each

successive one in a manner to be described hereinafter and shown in the drawings of which:—

Figure 1 is a portion of an elevation of a 5 calender machine showing one of my improved journal boxes and a portion of another.

Figure 2 is a horizontal longitudinal section on the line 2—2 of Figure 1.

10 Figure 3 is a vertical median section on line 3—3 in Figure 1.

Figure 4 is a perspective view of one of the adjustable bearing blocks, and its water jacket.

15 Figure 5 is a perspective view of the cam used in adjusting the bearing block shown in Figure 4.

Figure 6 is a fractional elevation of the roll side of the journal box housing showing 20 the oil gate, employed to prevent the oil from creeping along the shaft and out of the housing.

Referring now to the drawings in detail, I have shown the frame 1, of a calendering 25 machine which is provided with vertical runways 2 constructed in the sides of a slot running from top to bottom of the frame. The journal box 3 has ways 4 fashioned in the end walls of the journal housing 5, 30 which operate against the runways 2 and hold the journal slidably in the frame. Vertical guideways 6 on the ends of the journal box housing and gib 7 bolted to the housing opposite to the guideways engage the frame-work and serve to hold the journal box in 35 the frame of the machine. Adjustment screws 8 are provided in the journal housing and extending through the ways in the end walls thereof serve in taking up the wear between the runways in the frame and the 40 ways on the housing.

The journal box housing 5 is composed of a rectangular box-like portion 9 having upper and lower walls 10 and 11, end walls 45 12 and 13, and a rear wall 14 and is open at the front. The rear wall has an opening 15 to admit the shaft end of a roll. A cover 16 is provided for the front of the housing and is secured to the housing by means of the bolts 17. The cover is provided with openings 18 to permit access to the housing for minor repairs and inspection, said openings being closed by means of plates 19 held in place by the bolts 20 55 when the machine is in operation.

Disposed within the housing are the bearing blocks 21 constructed with walls enclosing a cavity 22 thus forming a water jacket for cooling the bearing by means of the 60 circulation of water therein. The inner wall 23 of the bearing block is fashioned with a semicircular face and provided with a bearing surface 24 having oil grooves 25 to admit oil between the shaft and the bearing. In 65 the front wall of the bearing block are two

threaded holes 26 to receive the pipes 27 of the water supply system. These pipes pass through slots 28 in the cover of the housing and are provided with links of flexible tubing 29 connecting the outlet of the block 70 of one journal with the inlet of that next below.

The bearing blocks are furthermore provided with channels 30 running lengthwise of the blocks and fashioned to receive and 75 contact with the cams 31, said cams being fashioned into shafts 32 at their ends which shafts are journaled in openings 33 in the housing and 34 in the cover respectively. The cams are rotatably held in the channels 80 of the bearing blocks by means of the plates 35 which are attached to the bearing blocks by means of screws. The outer end of the cam shaft is squared to receive a crank or wrench necessary to operate the cams. The 85 cam shafts extend through the cover of the housing and by rotating the cams as desired the bearing blocks may be adjusted into contact with the shaft of the roll. When the desired adjustment is obtained 90 the cam is locked in place by means of a set screw 36 in the cover of the journal or by a pawl and ratchet arrangement on the cam shaft.

A bronze bearing block is inserted in the 95 upper part of the housing and allowed to rest upon the shaft end of the roll. An oblong opening 38 is provided in the upper wall of the housing by means of which oil is supplied to the housing. The lower wall 100 of the housing is fashioned into a semicircular depression along the median line into which this oil is held at a sufficient height to provide an oil bath for the shaft end of the calender roll. Holes drilled in the 105 higher portions of the lower wall of the housing permit the oil to overflow and drip through the opening 38 of the housing below, and finally into a reservoir at the base of the machine from whence it is returned 110 to the topmost journal by means of a pump. The bronze bearing block 37 besides serving as an additional bearing surface for the shaft end of the calender roll, also serves to partly close the opening 38 against the intrusion of foreign matter, into the journal box.

The cover of the housing is furthermore provided with a central opening 39 threaded to receive the threaded shaft 40 of the end 115 thrust bearing 41. The inner end of the shaft 40 is provided with a flanged head 42 having a flange 43 fashioned to support the ball race 44 of the end thrust bearing. The outer end 45 of the shaft is squared to receive a crank by means of which the shaft 120 is turned and the thrust bearing brought into contact with the end of the shaft of the calender roll. When the desired adjustment is obtained, the bearing shaft is 125 130

locked in place by means of the lock nut 46. It should be noted that a bronze bearing could be used for end thrust instead of a roller bearing which has been described and illustrated.

5 The depression in the bottom of the housing designed to contain a quantity of oil for flooded lubrication of the shaft end of the calender roll and its relation to the location of the opening in the rear of the housing for purpose of admitting the shaft end, must of necessity be such as to nullify its intended purpose of retaining a necessary quantity of the oil, unless some means is provided to close the gap which remains between the shaft and the rim of the opening in the housing. For this purpose I have devised an oil gate 47 which is held in a mortise in the outer surface of the rear wall of the housing by means of bolts.

20 The fixed portion 48 of the oil gate is shaped into a pocket 49 in the bottom of which is a flat bow spring 50. A wiper 51 having a semicircular bearing surface to conform to the circumference of the shaft of the calender roll is inserted into the pocket 49 and is held in contact with the shaft end of the calender roll by the pressure of the spring 50. By this means any oil which may creep along the shaft is diverted and returned back into the journal box housing.

25 In practical operation, when the bearing in the journal becomes sufficiently worn to require realignment of the calender roll, this may be done by rotating one or both of the cams with the aid of a crank or wrench from the outside of the journal housing, likewise any inequality in the wear of the bearings 30 may be compensated in this manner.

35 Excessive end play may be compensated by a slight readjustment of the end thrust bearing in a similar manner, and without disturbing the journal box or its contents. 40 Repairs or replacements in the end thrust bearing may be made by simply removing one or both of the plates covering the openings in the cover of the journal box, while in case of repairs or renewal of the bearing 45 blocks and their mechanism the cover of the housing may be removed first disconnecting the water supply pipes, when the bearing blocks and cams may be removed without disturbing the calender roll or the remainder 50 of the journal box housing.

55 Having thus described my invention, what I claim as new and desire to secure by Letters Patent, is:—

1. In a journal box capable of receiving 60 the rotating shaft of a machine, a plurality of hollow bearing blocks, means for circulating water through the cavities in said bearing blocks, for cooling them, cams contacting with said bearing blocks by means of

which said blocks may be adjusted into desired contact with said rotating shaft, means for connecting misalignment of said shaft by operation of said cams, an oil-tight housing enclosing all of said bearings and parts and providing flooded lubrication of the 65 moving parts contained therein, an oil gate provided at the open end of said housing having a wiper in contact with said rotating shaft, and suitable means for holding said wiper in contact with said shaft and retaining the lubricant within the housing.

2. In a calender machine, a journal box for calender rolls comprising an oil-tight housing, a plurality of lateral bearing blocks, bearing surfaces on said bearing 70 blocks, said bearing blocks being provided with recesses, cams in said recesses and applied to the sides of said recesses, means for actuating said cams causing said bearings to be brought into contact with the shaft 75 of a calender roll and means for locking said cams against releasing such adjustment.

3. In a calender machine, a journal for calender rolls, comprising an oil-tight housing, an oil reservoir to furnish flooded lubrication to the bearings in said housing, a plurality of bearing blocks enclosed in said housing, bearing surfaces on said bearing blocks capable of holding the shaft of a calender roll in journaled suspension, recesses 80 in said blocks, cams operating in said recesses by means of which said blocks are brought and held in contact with the shaft journaled therein, portions of said bearing blocks being fashioned into water jackets, 85 means for supplying and circulating water in said water jackets for cooling said bearings, means for adjusting and controlling said cams externally of the housing of said journal box, means for preventing leakage of 90 oil supplies from said housing, and means for locking said cams in a desired adjustment.

4. In a calendering machine, wherein a series of rolls rest on each other, guides for journal boxes, boxes in the guides, and engaging the spindles of the rolls, said boxes having bearing blocks therein, adjustable laterally within the boxes, said blocks being formed with water passages, means opening into the passages through the housings for 100 supplying water thereto, said means being interconnected in vertical series, so as to set up lines of flow of cooling water through the bearing blocks of the series.

5. A journal for the spindle of a calender roll comprising a journal box having bearing blocks therein adjustable laterally within the box, said blocks being formed with water passages, means for supplying water to said passages, and a supporting member for the 105 box provided with a vertically aligning guide.

JOHN H. REEDY
